UNITED STATES PATENT OFFICE.

WINTHROP L. JACOBS, OF JERSEY CITY, NEW JERSEY, ASSIGNOR TO HARTFORD CARPET COMPANY, OF HARTFORD, CONNECTICUT.

DESIGN FOR CARPET.

SPECIFICATION forming part of Design No. 12,069, dated December 21, 1880.

Application filed September 18, 1880. Term of patent 3½ years.

To all whom it may concern:

Be it known that I, WINTHROP L. JACOBS, of Jersey City, in the county of Hudson and State of New Jersey, have invented a new and original Design for a Carpet, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The design consists of flower-like figures and rosette-shaped figures scattered over a background, and having vines embellished with leaves and buds running between and filling the interstices between the various figures.

20 The figure A is a flower-like figure resembling a widely-opened rose.

The figure B is a flower-like figure resembling somewhat a tulip.

The figure C is a rosette-shaped figure.

25 The figure D is a half-rosette resembling the half of a sunflower.

The figure E is a flower-like figure widely open with a large center.

The figures F G H J O P Q R also represent flower-like figures of different sizes and somewhat different shapes scattered over the background, and all of them with their leaves widely open.

30 The figure I somewhat resembles an open daisy.

The figure K is a flower-like figure with a projecting center, somewhat like a cornucopia.

The figure L is a flower-like figure having projecting from its upper edge a vine with dividing leaves and a flower between them.

40 The figure M is a flower-like figure, having two projections on one side resembling claws.

The figure N is a semicircular flower-like figure.

45 The figures a b d e f g h represent the vines which appear in the interstices between the various figures and connect them.
